UNITED STATES PATENT OFFICE

167,510

GIRDLE

Arthur Goldstein, New York, N. Y., assignor to
Tru Balance Corsets, Inc., New York, N. Y., a
corporation of New York

Application December 6, 1951, Serial No. 17,633

Term of patent 14 years

(Cl. D20—2)

To all whom it may concern:

Be it known that I, Arthur Goldstein, a citizen of the United States of America and a resident of New York, New York, have invented a new, original, and ornamental Design for a Girdle, of which the following is a specification, reference being had to the accompanying drawing, forming a part hereof.

Figure 1 is a front perspective view of a girdle showing my new design;

Figure 2 is a rear perspective view of that shown in Figure 1;

Figure 3 is a view similar to Figure 1 showing other side thereof; and

Figure 4 is a view similar to Figure 2 showing other side thereof.

I claim:

The ornamental design for a girdle, substantially as shown.

ARTHUR GOLDSTEIN.
